UNITED STATES PATENT OFFICE

ALBERT E. CILLEY, OF MELROSE, MASSACHUSETTS

PROCESS AND TOOL FOR SURFACING BLANKET CYLINDERS

Application filed July 3, 1928. Serial No. 290,131.

This invention relates to the surfacing of blanket cylinders or rolls used in printing presses. In one aspect, it consists in a novel process of surfacing such rolls and in another aspect it consists in a new and improved tool for carrying out the process.

The blanket cylinder in a printing press is disposed opposite to and in cooperative relation with the plate cylinder which carries 10 cylindrical plates of type upon its surface. The paper being printed is passed between the plate cylinder and the blanket cylinder, the latter forming a yielding backing for the paper so that a clear impression is made 15 thereon by the type. Blanket cylinders or rolls are usually built up upon a steel core of closely woven woolen fabric with an outer layer of virgin wool and a skin of flexible pyroxylin or rubberized compound.

20 The type plates on the plate cylinder are usually spaced from each other longitudinally of the cylinder about 1" apart. The cylinders roll upon each other under considerable pressure and after a period of continuous use, the blanket cylinder takes the 25 impression of the type plates so that ribs, called bolsters, are formed opposite to the spaces between the type plates. If type plates of the same width were always used, this 30 would not be objectionable but it frequently happens that it is desirable to set up a type plate of double width, or a double-truck plate as it is called, in order to print a double page impression. Under these circumstances, the 35 ribs or bolsters formed in the blanket plate produce an excessive pressure upon the portion of the double-truck plate located opposite to them, so much so that it tends to cut the paper and make an uneven impression 40 in the sheet. Prior to my invention, it was the practice to surface blanket rolls and remove the ribs by burning and ironing the rib portion with a soldering iron or similar tool, or in some cases the rib has been reduced by a knife or chisel but always under 45 uncertain conditions requiring special skill in the operator and involving a long and arduous operation.

50 My object aims to improve these conditions and to provide first, a new process of surfac-

ing blanket rolls in an improved manner and, second, a tool by which the process may be successfully carried out. I have discovered that the bolster of a blanket roll may be removed in its entirety and the process of 55 my invention is characterized by cutting two clean circumferential lines through the skin of the blanket roll and into the wool beneath it, removing completely the skin between the two lines and a portion of the wool adjacent 60 thereto, so as to form a definite, clean-edged zone where the bolster was formerly located. This method may be carried out by hand or by a power-driven tool and the bounding lines of the cut-out zone may be formed singly or simultaneously; also the intermediate portion may be removed after the bounding lines have been formed, or at the same time. I prefer, however, to carry out the various 65 steps of the process substantially simultaneously and, accordingly, my invention in one of its aspects consists in the process of 70 surfacing ribbed rolls which is characterized by simultaneously defining a circumferential zone coinciding substantially with the rib 75 and progressively removing the surface material in the defined zone.

The best means known to me for carrying into effect the process of my invention consists in a tool having a power-driven cutter 80 and a guide member or shoe curved to fit the contour of the roll to be operated upon and serving to locate the cutter with reference to the roll. As herein shown, two such 85 shoes are employed and the cutter is located between them. In this way, the cutter is positioned correctly with respect to the curved surface of the particular roll being operated upon and the trimming operation is effected with reference to the identical surface contour being treated.

Another feature of the invention consists in guiding means in the tool arranged to act in cooperation with the rib or bolster to be trimmed so as to position the tool as a whole 90 upon the rib or so that the path of the driven cutter upon the surface of the moving roll coincides with the rib. The invention includes as a further feature a follower located 95 behind the cutter for positioning the tool 100

by the cut-out track left in the surface of the work by the cutter. Usually, it is convenient to place the tool upon the surface of the roll and hold the tool stationary while the roll, in the press, is slowly turned beneath it. The path of the cutter upon the roll is in the latter case, accordingly, produced by the movement of the roll although the guiding and positioning function is the same whichever of the two elements is actually moved.

As herein shown, the cutter is arranged to rotate about an axis normal to the surface of the roll and is driven by a vertical motor, although the shape of the cutter and the disposition of the motor are not essential. The cutter herein shown is arranged for adjusting movement toward and from the surface of the roll under manual control and this constitutes another feature of the invention which may be realized in various mechanical forms. Preferably also, an adjustable stop is provided for limiting the downward movement of the cutter so that the depth of the cut or track made by it may be accurately and positively determined.

Other features of the invention consists in the provision of handles for manipulating the tool and placing it upon the roll, and in the provision of convenient grinding mechanism included as a part of the construction and serving as a convenient means for resharpening the cutter. Some elements of novelty, moreover, will be found in the cutter which I have disclosed in connection with the tool and which comprises a toothed rotary cutter, concave in its general shape and dished in the surface which is disposed toward the roll.

These and other features of the invention will be best understood and appreciated from the following description of a preferred embodiment of the tool, together with the description of the manner of its use in carrying out the process of my invention. In the accompanying drawings,

Fig. 1 is a view in perspective showing a portion of a blanket cylinder with the bolster cutting tool in position upon it;

Fig. 2 is a central sectional view through the tool and a portion of the blanket roll;

Fig. 3 is a view in longitudinal section on the line 3—3 of Fig. 1;

Fig. 4 is a fragmentary view in elevation of corresponding rolls on the other side of the tool; and

Fig. 5 is a view in perspective of the cutter used in the tool.

The blanket roll comprises a steel core 10, upon the surface of which is secured, by cement or otherwise, a layer 12 of closely woven woolen textile material, then a thinner layer 14 of virgin wool and, finally, a surface skin 16 of a yielding flexible pyroxylin or rubberized compound. This cylinder or roll, therefore, has a tough and fairly hard skin

which is backed up solidly but yieldingly by the textile fabric beneath it. As already explained, the blanket roll cooperates with the type plate roll, the two being pressed together and rotated with the paper to be printed running between them. The rib or bolster 18 shown in Fig. 1 is formed in the blanket cylinder in the space between adjoining type plates as a result of continuous operation for a considerable time. It is caused by the action to that part of the cylinder not subjected to pressure in gradually bulging outwardly. It will be apparent that if a double-truck type plate is to be used which will bridge that portion of the blanket roll in which the rib 18 occurs, the latter must be smoothed or removed, or else the pressure of the two rolls will be localized within the area of the rib, with undesirable results.

I have discovered that the material of the rib or bolster 18 may be entirely removed from the blanket roll even to the extent of leaving a shallow channel in place of the bolster and that a blanket cylinder so surfaced may be used with entire and complete satisfaction in cooperation with a double-truck type plate. To effect this result, I have evolved a method characterized by first marking or scoring upon the skin of the blanket roll the portion to be removed, thus defining and limiting the ensuing and dependent steps of the process. This step may be carried out by sharp-edged scoring rolls and these constitute an element of the tool which will presently be described.

In practicing the process of my invention, the material between the two marks thus formed is then removed by any suitable form of cutter which will cleanly cut the skin of the blanket roll, leaving a circumferential zone, with clean-cut edges. Preferably and in most cases, a small portion of the wool layer 14 beneath the skin 18 will also be removed. I have found it possible to use a toothed rotary cutter of such design as to cut through the skin of the cylinder roll, removing the skin and also a portion of the wool layer simultaneously. The steps above set forth may be carried out progressively to good advantage and, as herein shown, the blanket roll is slowly rotated beneath the scoring rolls and a driven cutter so that the bolster 18 is progressively removed and in its place a shallow circumferential channel is produced in the cylinder.

Referring now to the construction of the tool which I prefer to employ in practicing my process: This comprises a frame 20 having parallel side walls to which are secured contact shoes 22 and 24 having a curvature corresponding to the cylindrical curvature of the cylinder to be operated upon. As blanket cylinders vary somewhat in diameter, the contact shoes 22 and 24 are arranged in pairs, pivotally connected to the side walls of the

frame 20 so that they may be adjusted to accommodate rolls of different diameter. The inner ends of the contact shoes 22 and 24 are reduced in thickness, lapping over each other and pivotally connected to the frame 20 by pivot screws 26. These may be loosened to permit adjustment of the contact shoes and then tightened in adjusted position. Each pair of contact shoes is connected by a stationary cross shaft 28 having a pair of anti-friction rolls 30 which project slightly below the lower edge of the contact shoes 22 and 24 and run upon the surface of the blanket roll. These also permit the adjustment for different diameters of roll, as they constitute the effective contact points of the whole assembly.

Within the anti-friction rolls 30 upon each shaft 28 is located a pair of loose sleeves 32 or spacers which serve to locate a roll 34 on the forward shaft 28 and a roll 36 on the rear shaft. The roll 34 has two sharp-edged flanges, the inner surfaces of which taper toward each other. This serves the double function of locating the tool centrally with respect to the bolster 18 and of scoring the skin surface of the blanket roll to define the area to be removed. The roll 36, on the other hand, has flanges with surfaces which taper outwardly and thus acts to locate the rear portion of the tool with reference to the shallow channel formed in removing the bolster 18.

Secured to the frame 20 is the casing 40 of a vertical motor, having a driven shaft 42 which carries a toothed cutter 44 having teeth with sharp radially disposed cutting edges and being dished upon the surface disposed toward the blanket cylinder. The cutter is carried by a sleeve 46 which fits over the shouldered lower end of the motor shaft 42 and has parallel slots in its upper end to receive a cross pin 48 in the end of the motor shaft. The sleeve 46 with the cutter 44 is free for limited sliding movement upon the motor shaft 42 having, in effect, a spline connection therewith and being maintained normally in its upper or inoperative position in which it is out of contact with the bolster 18.

The sleeve 46 is surrounded by another sleeve 50 which is free to slide vertically in bearings 52 formed in the web or bridge 54 of the frame 20 and has a flange at its upper end which is received between the forks of a shifting lever 56, pivotally mounted between ears 58 on the web 54 and formed as a finger piece 60 at its outer end. A ring 64, secured to the inner sleeve 46, prevents that from dropping out of engagement with the motor shaft 42.

Handles 70 and 72 project from opposite sides of the frame 20. The handle 70 on the right side of the tool, as shown in Fig. 2, is slotted to receive the outer end of the shifting lever 56 and a compression spring 61 interposed between the outer end of this

lever and the inner wall of the handle 70 tends always to retain the cutter in its uppermost position on the shaft 42 of the motor. An adjustable stop 74 is provided in the handle 70 for limiting the upward movement of the shifting lever 56 and, consequently, the downward movement of the cutter 44.

The motor 40 is of any well-known commercial construction and it is, accordingly, unnecessary to describe the details thereof further than to say that lead wires 80 are brought to it through the left handle 72 and that current is controlled through a snap switch 76, located in the handle 72. A bracket 82 is secured to the motor frame and carries a small lamp 84 which is disposed beneath the overhanging portion of the frame 20 and in position to illuminate the portion of the blanket cylinder to be operated upon.

The upper end of the motor shaft is provided with a vertical grinding wheel 90 which is surrounded by a casing 92 formed on the upper head of the motor. A bracket 94 secured to or forming a part of the head carries a radially movable spindle 96, having a screw-threaded inner end upon which a cutter may be temporarily mounted for the purpose of grinding its end surface and forming the spherically concaved or dished contour desired.

It will be seen that I have produced a self-contained integral tool including the scoring and locating rolls, the driven cutter and the handles 70 and 72 for moving and placing the tool as a whole. In carrying out the process of my invention, the tool is located upon the surface of the blanket roll while the latter occupies its usual position in the printing press. As already stated, the tool is located with reference to the bolster 18 by the tapering flanges of the roller 34. The cutter is set in motion by tripping the switch 76 and the blanket roll is turned slowly in the direction of the arrow shown in Fig. 1. The operator then depresses the finger piece 60 of the shifting lever 56, moving the cutter 44 downwardly, whereupon it cuts its way through the skin of the blanket roll and into the bolster 18. The ultimate cutting position of the cutter 44 is determined by the adjustable stop 74, as already stated.

Having brought the cutter to this position, the blanket roll continues to turn until a complete circumferential zone has been cut out from the skin of the roll and a very shallow channel produced in the surface thereof, as indicated in the rear side of the roll in Fig. 1. When the cylinder has made one complete revolution with the cutter in its operative position, the finger piece 60 is released, whereupon the cutter moves into inoperative position and the motor is stopped by throwing the switch 76. The operation of surfacing the roll is thereupon complete and the printing operation may be resumed without further delay. It will be understood that

a cutter may be ground upon the spindle 96 at any time whether the tool is in position upon a blanket cylinder or not.

Having thus described my invention, what I claim as new and desire to secure by Letters Patent is:

1. A bolster cutting tool comprising a driven cutter, spaced shoes disposed on either side of the cutter, curved to fit the contour of the roll to be operated upon, and serving to locate the cutter with reference to the surface thereof, and means disposed between said shoes for positioning the tool as a whole with reference to a bolster in the roll.
2. A bolster cutting tool comprising a driven cutter, a frame carrying said cutter and having anti-friction rolls, which, together with the cutter, are disposed substantially upon an arc corresponding to the curvature of the roll to be operated upon, and means disposed in substantial circumferential alignment with the cutter for positioning the tool as a whole with respect to a bolster in the roll.
3. A bolster cutting tool comprising a driven cutter with an end cutting face, a frame carrying said cutter and having anti-friction rolls, which, together with the cutter, are disposed substantially in a cylindrical surface corresponding to the curvature of the roll to be operated upon, and means disposed at the leading end of the tool for positioning the same with respect to a bolster in the roll.
4. A bolster cutting tool comprising a driven cutter with an end cutting face, a frame carrying said cutter and shaped to locate it with its axis normal to the cylindrical surface of the moving roll to be operated upon, and means in the frame for positioning the tool as a whole in a circumferential path with respect to the roll.
5. A tool for trimming a ribbed roll, comprising a driven cutter, and a frame carrying said cutter and having means for locating the tool upon the cylindrical surface of the moving roll to be operated upon, and means in the frame acting upon the rib to position the tool as a whole in a path coinciding with the rib.
6. A tool for trimming a ribbed roll, comprising a driven cutter, and a frame carrying said cutter and having spaced gauge rolls for engaging the rib and positioning the tool as a whole with respect thereto.
7. A tool for trimming a ribbed roll, comprising a frame shaped to fit the cylindrical surface of the roll, a driven cutter carried thereby, spaced guide members in the forward portion of the frame for positioning the tool upon the rib, and a follower in the rear portion of the frame for positioning the tool by the cut-out track left in the roll by the cutter.
8. A tool for surfacing a ribbed blanket roll, comprising a frame shaped to fit the cy-

lindrical surface of the roll, a driven cutter carried thereby, and a follower carried by the frame behind the cutter for positioning the tool by the cut-out track left in the roll by the cutter.

9. A bolster cutting tool for a blanket roll, comprising a frame with members shaped to fit circumferentially upon the roll, and a motor driven cutter with an end cutting face disposed in the frame with its axis normal to the curvature of the surface of the roll.

10. In a bolster cutting tool for a blanket roll, a toothed cutter, and means for mounting said cutter with its axis normal to the roll contour, said mounting means being movably engageable with the roll to travel the cutter thereabout.

11. A tool for surfacing a ribbed roll, comprising a frame with curved locating surfaces, a driven cutter mounted in the frame, means for maintaining the frame in position to straddle the rib of the roll, and manually controlled means for moving the cutter toward or from the plane of the locating surfaces.

12. A tool for surfacing a ribbed roll, comprising a frame with curved locating surfaces, a motor driven cutter disposed to rotate about an axis normal to the curvature of the plane of said locating surfaces and being yieldingly maintained in an elevated position, manually controlled means for moving the cutter downwardly, and an adjustable stop for limiting such movement.

13. A portable tool for surfacing a ribbed blanket roll, comprising a frame having curved contact pieces, a vertical motor mounted in the frame having a driven cutter splined to the lower end of its shaft and a grinder mounted on the upper end thereof, and handles projecting from the sides of the frame, one carrying a switch for the motor and the other carrying an adjusting device for the cutter.

14. A tool for surfacing a ribbed cylinder, comprising a frame, a motor driven cutter carried thereby, contact pieces associated with the frame having provision for adjustment to accommodate cylinders of different diameters, and rib engaging guides carried by said contact pieces.

15. A tool for surfacing a cylinder, comprising a frame, a motor driven cutter carried thereby, and sharp-edged scoring rolls located in advance of the cutter for marking on the surface of the cylinder the portion of its surface to be removed by the cutter.

16. The process of surfacing blanket cylinders having bolsters therein which consists in cutting through the skin of the cylinder in circumferential lines at each side of the bolster and removing the skin between said lines together with a portion of the material beneath the skin.

17. The process of surfacing blanket cylin-

ders having bolsters therein which consists in rotating the cylinder slowly, progressively cutting through the skin of the cylinder in parallel lines and simultaneously removing the skin between said lines.

18. The process of removing bolsters from blanket cylinders which consists in marking two parallel circumferential lines about the cylinder which include the bolster between them, dropping a rotary cutter through the skin of the cylinder between said lines, and turning the cylinder slowly to form a clean-edged zone with its surface depressed below that of the cylinder.

CERTIFICATE OF CORRECTION.

Patent No. 1,752,940.

Granted April 1, 1930, to

ALBERT E. CILLEY.

It is hereby certified that error appears in the printed specification of the above numbered patent requiring correction as follows: Page 4, line 78, claim 10, after the word "cutter" insert the words "dished in its end surface"; and that the said Letters Patent should be read with this correction therein that the same may conform to the record of the case in the Patent Office.

Signed and sealed this 6th day of May, A. D. 1930.

(Seal)

M. J. Moore,
Acting Commissioner of Patents.
